UNITED STATES PATENT OFFICE.

HENRY EDWARD STROHECKER, OF ENON VALLEY, PENNSYLVANIA.

PISTON-TOOL.

1,325,177.

Specification of Letters Patent   Patented Dec. 16, 1919.

Application filed March 13, 1919. Serial No. 282,461.

To all whom it may concern:

Be it known that I, HENRY EDWARD STROHECKER, a citizen of the United States, and a resident of Enon Valley, in the county of 5 Allegheny and State of Pennsylvania, have invented a new and useful Improvement in Piston-Tools; and I do hereby declare the following to be a full, clear, and exact description thereof.

10 My invention relates to tools for pistons, and has special reference to such devices for use in replacing pistons having movable packing rings within their cylinders, such as in automobile motors, etc.

15 The object of my invention is to form a cheap, simple and efficient tool for replacing pistons, which can be made in one piece, and will enable the replacing of the piston within the cylinder easily and quickly and 20 without injury to the piston, its rings or the cylinder.

A still further object of the invention is to provide a piston replacing tool which will not contain any operative parts to be handled or moved in using the tool, which are liable to become separated, misplaced or lost, when they are desired, as well as such a tool which can be used not only for replacing the 25 piston into either end of the cylinder, but 30 can also be used as a gage to determine the size of the piston rings to be used in the pistons.

To enable others skilled in the art to which my invention appertains to construct 35 and use my improved piston replacing tool, I will describe the same more fully, referring to the accompanying sheet of drawings, in which:

Figure 1 is a side elevation of a piston 40 ready to be placed within a cylinder (which is shown in section) and having my improved piston replacing tool in position for operation;

Fig. 2 is a similar view showing the tool 45 in position for replacing the piston within the cylinder by engaging with the lower or oil ring on the piston;

Fig. 3 is a top plan view of the tool;

Fig. 4 is a cross-section of the same; and

50 Fig. 5 is a sectional view showing another form of the tool.

Like symbols of reference herein indicate like parts in each of the figures of the drawings.

55 As illustrated in the drawings, 1 represents the cylinder of an engine or motor,

such as is used on an automobile or for other purposes, which is provided with the usual bore 2 therein for the reception and operation of the usual piston 3 within the same 60 and which has the usual split packing rings 4 and oil ring 5 mounted in the recesses 6 within the same.

The piston replacing tool is shown at 7 and comprises a solid integral ring, which 65 is formed of any suitable metal, such as iron or steel, and is of circular shape.

The ring 7 has its bore 8 corresponding to and of the same diameter as the bore 2 of the cylinder 1, upon which it is adapted to 70 engage, and the wall 9 forming such ring is provided with the two flat side faces 10 and 11. Within the face 10 and extending outward from the bore 8 of the ring 7 is the chamfered face 12 which, when flat, is preferably formed at the desired angle, and such face instead of being flat as shown, can also be of rounded or curved form as shown in Fig. 5.

In the use and operation of my improved 80 piston replacing tool 7, when it is desired to replace the piston 3, as shown in Fig. 1, the tool is placed around the piston and against the end of the cylinder 1, so that in such position the face 11 on the tool 7 will come 85 against said cylinder end. While the tool 7 is thus held in this position by the operator's hands, the piston 3 is forced into the bore 2 of the cylinder 1, which will thereby allow the rings 4 and 5 to come in contact 90 with the inclined face 12 on the tool to thus force said rings into their recesses 6 in the piston and permit the piston and its rings to enter the bore of the cylinder.

In case the lower or oil ring 5 on the piston 3 has jumped out of the bore 2 of the cylinder 1 and it is desired to replace the same within the piston and the piston back into the bore of the cylinder with such ring in place, the tool 7 is placed around the piston with its face 10 toward the end of such cylinder, so that the inclined face 12 on the tool will come in contact with the lower edge of said ring. When the tool 7 is in this position and upon forcing the same upward 100 by the hands of the operator, so that the face 10 on the same will come against the lower end of the cylinder 1, the inclined face 12 on the tool will force the ring 5 into its recess 6 in the piston 3 and then the piston can 110 be forced upward into the bore of the cylinder.

In some makes of automobiles, below and cast into the lower end of each end cylinder, a strengthening rib is formed in the bearing supports, such rib being shown at 13 in Fig. 5 2, and in such case, the replacing tool can be provided with a notch 14 in the outer face 9' of the wall 9, so that such rib can fit into the same when the tool is placed around the piston for replacing the lower ring 5 10 and piston into the bore of the cylinder as above described. The face 9' can also be milled for handling.

It will be evident, as shown in Fig. 4, that the tool 7 can also be used as a piston 15 gage and for testing the size of new, worn or oversize piston rings by placing one of such rings within the bore 8 of the same, which will also show if any space is formed at the split end of the ring.

20 Various other modifications, changes and applications of my improved piston tool may be resorted to within the scope of the appended claim, without departing from the spirit of the invention or sacrificing any of 25 its advantages.

It will thus be seen that my improved piston tool can be easily and cheaply manufactured and sets of the same can be kept for use with various sizes of pistons, while 30 in the use of the same it will allow the piston to be easily and conveniently com-

pressed and guided through the same and into the cylinder, and at the same time such piston is also guided into the cylinder. The tool is easily handled in its operation, and 35 being composed of a single integral part cannot get out of order or fail to operate, either in replacing pistons and their rings or in acting as a gage in testing pistons and rings. 40

What I claim as my invention and desire to secure by Letters Patent is:

A device of the class described for use in replacing pistons having rings within cylinders having a strengthening rib at the 45 lower end of the same, comprising a tool formed of a solid integral circular ring adapted to be placed over the piston and having two side faces and a bore corresponding to and of the same diameter as the bore 50 of the cylinder, said ring having a chamfered portion extending out from its bore to one of said side piston rings, and a notch in the outer face of said ring for fitting around said rib. 55

In testimony whereof, I, the said HENRY EDWARD STROHECKER, have hereunto set my hand.

HENRY EDWARD STROHECKER.
